AIR GUN

William S. Wells, Palo Alto, Calif., assignor to
 Daisy Manufacturing Company, Plymouth,
 Mich., a corporation of Michigan

Application January 12, 1949, Serial No. 70,528

7 Claims. (Cl. 124—15)

1

This invention relates to air guns and more particularly to an air gun construction which will permit a projectile to be propelled therefrom in a much more efficient and simple manner than has been heretofore known.

At the present time there are two general types of air guns, namely, spring type guns and compressed air type guns. In the conventional spring type air gun, a coil spring, having a plunger connected therewith, is compressed, and when the spring is released the plunger moves so as to simultaneously compress a charge of air in a chamber and force the air out of the chamber and into the gun barrel, giving velocity to a projectile in the barrel and propelling the projectile out of the muzzle end thereof. This type of gun is very inefficient, as the spring must necessarily have a rather long movement, such as two and a half or three inches, and its working force, when released, is therefore far from constant. Due to this long movement, a large expenditure of effort is required to compress the spring, and when the spring is released the force exerted thereby materially decreases as the spring expands. Furthermore, as the air chamber is at all times in open communication with the barrel, it is not possible, when the plunger and spring are released, to maintain a constant propelling force against the shot. The muzzle velocity of the shot is therefore relatively low, and the action of the gun is extremely inefficient due to the large amount of wasted energy.

Conventional compressed air guns are also highly inefficient. In this type of gun, air is pumped into a closed chamber until a desired pressure within the chamber is reached. If it is desired to build up a substantial pressure within the chamber, a large amount of work must be expended by the user, thus making it a real chore to obtain an air charge of substantial pressure which will in turn impart a high velocity to the projectile propelled from the barrel. When the trigger of this type of gun is pulled, the air chamber is communicated with the barrel and compressed air flows from the chamber into the barrel, behind the projectile, so as to propel the latter through the barrel. The air pressure behind the projectile materially decreases as it propels the projectile through the barrel, due to the increase of volume, so that the initial chamber pressure is not maintained. In any air gun one of the main factors regulating the velocity of the projectile is the mean effective air pressure exerted on the projectile during its passage through the barrel. Therefore, as the pressure of the compressed air flowing through the barrel rapidly decreases, it will be appreciated that the velocity of the pro-

2

jectile will be determined by the mean pressure of the compressed air between the initial high pressure in the chamber and the relatively low pressure in the barrel at the time the pellet reaches the muzzle end thereof. The ordinary compressed air gun is therefore extremely inefficient, due primarily to the fact that the initial compressed air pressure continually drops during the movement of the projectile through the barrel, thus wasting a great amount of energy.

The primary object of this invention is to provide an air gun which may be of either the high or low velocity type, or of the single shot or repeater type, and in which as high a projectile velocity as possible is obtained with the expenditure of the least amount of energy; that is, the provision of an air gun construction which is as efficient as possible and in which the initial pressure of a compressed air charge is substantially maintained for at least a predetermined extent of the movement of the projectile through the barrel, after the charge is released from its chamber and flows through the gun barrel thereby eliminating the waste of energy which occurs in all known air guns.

It is a still further object of this invention to provide an air gun of the aforementioned type, in which if the capacity of the compressed air charge is the same or larger than the capacity of the barrel, the initial pressure of the compressed air charge will be substantially maintained, even after the charge is released from its chamber and flows into the gun barrel.

It is a further object of this invention to provide an air gun, of the aforementioned type, in which a relatively high projectile velocity can be attained with the expenditure of a minimum amount of work on the part of the user.

It is a further object of this invention to provide, in an air gun of the aforementioned type, simple, inexpensive and novel means for substantially maintaining the initial pressure of an air charge after the charge is released and moves through the barrel of the gun to discharge the projectile for at least a predetermined extent of the movement of the projectile through the barrel.

It is a still further object of this invention to provide, in an air gun of the aforementioned type, a novel floating plunger arrangement for maintaining the aforementioned substantially constant air charge pressure in the barrel, behind the projectile, so as to compensate for projectile and barrel variances, and any other small leaks in the compressed air system during operation.

It is a still further object of this invention to

provide in an air gun, a chamber in which a charge of air may be compressed, incorporating novel, yieldable means whereby the volume of the chamber will be varied in accordance with the pressure of the air charge, and which chamber may be wholly or partially evacuated into the gun barrel behind a projectile therein, by means of a suitable valve, so that the pressure in the chamber will be substantially maintained in the barrel for at least a predetermined extent of the movement of the projectile through the barrel while the valve is open.

It is a still further object of this invention to provide a novel chamber construction and arrangement of the aforementioned type which may be employed in either an air gun of the single shot or repeater type.

It is a still further object of this invention to provide an air gun of the aforementioned type which is relatively inexpensive to manufacture, simple in construction, highly efficient in operation, easy to use and operate, and durable in construction.

These and other objects of this invention will become apparent from the following detailed description, taken in conjunction with the accompanying drawings, in which:

Figure 1 is a side elevational view of an air gun of this invention;

Fig. 2 is an enlarged, fragmentary, longitudinal sectional view of the structure illustrated in Fig. 1, illustrating the position of the parts when the gun is ready to be fired;

Fig. 3 is a sectional view of the structure illustrated in Fig. 2, taken along the line 3-3 thereof;

Fig. 4 is a fragmentary, sectional view, similar to Fig. 2, illustrating the position of the parts of the gun after it has been fired;

Fig. 5 is a fragmentary sectional view of the structure illustrated in Fig. 4, taken along the line 5-5 thereof;

Fig. 6 is a sectional view of the structure illustrated in Fig. 4, taken along the line 6-6 thereof; and

Fig. 7 is a fragmentary sectional view, partly in diagrammatical form, of a further embodiment of the invention.

In its broader aspects the air gun of this invention may be of any suitable type and includes a gun barrel through which a projectile may be propelled and a chamber in which a charge of air may be compressed by any suitable means. The chamber is connected with the gun barrel through suitable valve means so that upon actuation of the trigger mechanism of the gun the chamber may be wholly or partially evacuated into the barrel behind the projectile. The chamber incorporates novel, yieldable means whereby the volume of the chamber will be varied in accordance with the pressure of the air charge therein and which means are so constructed and arranged as to substantially maintain the chamber air pressure in the barrel, when the valve is open, for at least a predetermined extent of the movement of the projectile through the barrel. In the event that the capacity of the air charge evacuated from the chamber into the barrel is the same as or greater than the capacity of the barrel, then the initial chamber compressed air pressure will be substantially maintained in the barrel until the projectile is discharged therefrom. It will thus be appreciated that the air gun of this invention may be of either the single shot or repeater type, that is, the type in which a plurality of projectiles may be fired from the gun

without recharging the air chamber. While an air rifle is illustrated in the drawings, it will be understood that this invention is equally applicable to other types of weapons and mechanisms such as air pistols or the like.

The air rifle illustrated in Figs. 1-6, includes a stock 7, barrel 9 and trigger guard and housing 11, all interconnected in a suitable or conventional manner. A longitudinally extending tubular member or cylinder 15 is disposed below the barrel 9, and the rear portion thereof extends into the stock 7, while the intermediate and forward portions thereof are connected to the barrel, by any suitable means. A tubular cage member 17 is slidably mounted in cylinder 15 and has one end of link 19, of a scissors type pump mechanism 21, connected to the forward end thereof. The other end of link 19 is connected to an intermediate portion of a second link 23, which has its forward end pivotally connected to the cylinder 15, adjacent the front end thereof, and which carries a handle 25 on the rear end thereof. The handle 25, as can be seen in Fig. 1, is normally disposed in an abutting relationship with the under side of the cylinder 15, but is movable downwardly and forwardly, as shown in dot dash lines, so as to move the cage member 17 forwardly in the cylinder 15.

A plunger or piston 27 is slidably disposed in the cylinder 15 rearwardly of the cage member 17. The plunger 27 includes a seal 29, a nut 31 having a recess 32 in the front face thereof, and a rigid head 33. One end of a rod like member 35 is threaded into the plunger 27 and secured thereto in any suitable manner so as to properly retain the seal 29 between the head 33 and the nut 31. The opposite end of the rod 35 slidably extends through an aperture 37 in an abutment member 39 in the cage 17, and is adjustably connected thereto by means of a nut 41. A coil spring 43 surrounds the rod 35 and extends between the cage abutment member 39 and the plunger head 33. The spring 43 is normally set or preloaded, for reasons which will hereinafter appear, by tightening the nut 41 against the abutment member 39 so as to compress the spring the desired amount. It will thus be appreciated that a yieldable lost motion connection is provided between the plunger 27 and the cage 17; that is when the cage 17 is moved forwardly in the cylinder 15 by the scissors pump mechanism 21, the plunger 27 will be carried therewith, but the plunger 27 is movable relative to the cage 17 either against or under the action of the spring 43, as will hereinafter appear.

A valve body or plug 45 is disposed in the cylinder 15, rearwardly of the plunger 27. The plug or valve body 45 is rigidly connected to the inner wall of the cylinder 15 by any suitable means, such as soldering, so as to provide an air tight connection. The valve body 45 has a longitudinally extending passageway 47 therein which extends rearwardly from the front face thereof and which communicates with a vertically extending passageway 49, adjacent the rear of the valve body. A valve element 51 is slidably mounted in the valve body 45 and has its stem portion 53, which is of a smaller diameter than the passageway 47, extending rearwardly through the passageway 47 and slidably through an opening or bore 55, rearwardly of the vertical passageway 49. The valve element 51 has a head 57 formed on the forward end thereof, which normally seats against the outer face of a seal member 59, which is mounted on the front face of the

valve body 45, so as to close off the forward end of passageway 47. A spring 61 surrounds the exterior portion of the valve stem 53, rearwardly beyond the valve body 45, and one end of the spring abuts the rear face of the valve body 45 while the other end abuts a nut 63 which is threaded on the rear end of the valve stem. The spring 61 normally holds the valve head 57 in sealing engagement with the valve body seal 59 so as to close off the valve against the flow of air therethrough. A tapered tube 65 is tightly fitted into the upper end of the valve body vertical passageway 49 and has its upper end extending through an aperture 69 in the cylinder 15 and the barrel 9. The tube 65 is soldered into the aperture 69, so as to prevent any leakage of air therearound. The valve body longitudinal passageway 47 is therefore in unrestricted communication with the rear portion of the barrel at all times.

A bolt 75 is slidably mounted in the rear portion of the barrel 9 and has an outwardly projecting, rotatable bolt handle 77 connected thereto at 76. The bolt handle 77 projects outwardly through an L-shaped slot 79 in the barrel 9, and through a short vertical slot 78, in a sleeve-like member 80, which is slidably mounted on the rear portion of the barrel and connected to the rear portion of the bolt by pin 82. A pin 81 is connected to an intermediate portion of the bolt and extends downwardly through the sleeve 80 and a slot 83 in the barrel 9 and the cylinder 15 for cocking the gun hammer 84 in a manner which will be hereinafter described. The barrel 9 is provided, rearwardly of the valve body tube 65, with an elongated slot or notch 85, into which a pellet or shot member 87 may be dropped after the bolt 75 and sleeve 80 have been pulled rearwardly, as shown in dotted lines in Fig. 2. After the pellet 87 has been placed in the barrel slot or notch 85, the forward movement of the bolt 75 will carry the pellet 87 to a position in the barrel just forwardly of the valve body tube 65. The bolt 75 therefore cocks the gun and properly positions the pellet for propulsion from the barrel, in a manner which will be described.

A plug member 91 is secured in the extreme rear end of the cylinder 15 and is provided with a recess 93 in the front face thereof, in which one end of a coil spring 95 is received. The plug member 91 is also provided with an aperture or bore 97, rearwardly of the recess 93, in which the rear end of an elongated cylindrical pin member 99 is secured. The hammer 84 is slidably supported on the pin 99, and the rear portion of the hammer slidably fits the bore of the cylinder 15, while the front portion thereof is reduced in diameter so as to provide an annular hammer shoulder 103. The back face of the hammer 84 is recessed at 105 to receive the forward end of the spring 95. The pin 99 supports and guides the hammer 84 for forward movement into engagement with the valve stem 53 in the valve body 45.

When the bolt 75 is pulled rearwardly, the bolt pin 81 engages the shoulder 103 of the hammer 84, so as to slide the hammer rearwardly to its cocked position, and compress spring 95. The hammer is held in its cocked position by means of a sear 107 which is supported on a pin 109 in the trigger guard and housing 11. The sear 107 is of the hair pin type and one leg thereof extends through a slot 108, in the underside of the cylinder 15 so as to engage the hammer shoulder 103, while the other leg thereof engages a nose portion 111 of a trigger 113, which is

mounted in the trigger guard and housing 11 by means of pivot pin 115. The trigger 113 is normally held in a cocked position for actuation by suitable means such as a spring 117. When the trigger is pulled, it rotates the sear 107 so as to release the hammer for forward movement under the action of the spring 95.

In order to operate the gun, the scissors handle 25 is pulled downwardly by the user so that the cage 17 and plunger 27 are moved forwardly in the cylinder 15 until the plunger 27 passes beyond an air inlet opening 121 in the underside of the cylinder, as shown in dot and dash lines in Fig. 2. The scissors handle 25 is then pulled upwardly and will move the cage 17 and plunger 27 to the rear so as to compress the air in the cylinder 15 between the plunger and the valve body 45. As the plunger 27 moves rearwardly the pressure of the air in the cylinder chamber between the plunger and valve body will be increased.

Due to the fact that the spring 43 between the cage and plunger has been preloaded or set a predetermined amount, there is a predetermined force exerted against the plunger by the spring. This force of course, depends upon the K factor of the spring as well as the amount of set therein. The plunger 27 will continue to move rearwardly in the cylinder and compress the air until such a time as the force exerted on the plunger by the air exceeds the force exerted on the plunger by the spring in its preloaded condition. When this condition occurs, the plunger will start to move forwardly in the cylinder, relative to the cage 17, and will compress the spring 43. It will thus be appreciated that after the scissors handle 25 is back in its normal position the spring 43 will have been compressed until the forces exerted on each side of the plunger by the compressed air and the spring are equal.

Preferably, for single shot guns, such as the one illustrated, the capacity or volume of the cylinder chamber, in which the air is compressed, is relatively small, and the amount of compression of the spring 43, caused by the compressed air force, is relatively small, due to the fact that the spring was initially preloaded. That is, the spring is constructed so as to be capable of exerting a force equal to that exerted by the compressed air, irrespective of the size of the chamber, by being operatively compressed only a relatively small amount, and without bottoming. It will of course, be appreciated that the volume of the cylinder chamber and the value of the spring may be varied in order to obtain various firing conditions, as well as for different types and sizes of guns.

After the scissors pump mechanism has been actuated so as to charge the gun, the bolt 75 and sleeve 80 are pulled rearwardly, so as to cock the hammer 84, as previously described, and a pellet is placed in the barrel slot or notch 85. When the bolt and sleeve are moved forwardly, the bolt positions the pellet just ahead of the valve body tube 65 and the hammer is held in its cocked position by the trigger sear 107. When the trigger is pulled the sear 107 releases the hammer, and the hammer moves forwardly under the action of spring 95 so as to engage the end of the valve stem 53 and move the valve head 57 off of its seat, against the action of the valve stem spring 61.

The compressed air in the cylinder chamber then flows through the valve body passageways 47 and 49, through the tube 65 and into the barrel

9 just rearwardly of the pellet 87 so as to move the pellet 87 forwardly through the bore of the barrel and out of the muzzle end thereof. As soon as the valve element 51 has been opened the volume of the compressed air will begin to increase, which would normally tend to decrease the pressure of the air. However, the initial pressure of the air is substantially maintained with the construction of this invention due to the fact that as soon as the volume increases, and the pressure tends to decrease, the spring 43 starts to expand and use its stored up energy to move the plunger 27 rearwardly so as to reduce the volume in the cylinder chamber, between the valve body 45 and plunger 27, and maintain a substantially constant air pressure in the cylinder chamber and barrel 9, behind the pellet 87. Due to the precompression of the spring and the relatively small expansive movement of the spring, there will be only a very small or infinitesimal drop in the air pressure, due to the loss of energy in the spring as it expands. A substantially constant tension or force is therefore exerted against the plunger and there is only a negligible loss of energy as the spring expands. Therefore, if the capacity of the compressed air chamber, between the plunger 27 and valve 45, is the same as or larger than the capacity of the barrel 9, the pellet will be propelled through the barrel and out of the muzzle end thereof by a pressure of air which is substantially the same as the initial pressure in the chamber. Therefore, practically all of the compressed air is used, without any drop in the initial pressure, and with only a very slight loss of energy. The floating plunger arrangement also permits the substantial maintenance of the initial cylinder chamber pressure, even though there are small leaks in the compressed air system, during the firing operation. That is, the spring 43 will move the plunger rearwardly so as to compensate for any drop in air pressure caused by barrel or pellet variances, or any other small leak in the gun. After the pellet has been discharged from the muzzle end of the barrel, the plunger 27 and operating parts of the mechanism will be disposed in the position illustrated in Fig. 4. If the capacity of the compressed air chamber is less than the capacity of the barrel, the initial compressed air pressure will be maintained in the barrel for only a predetermined extent of the movement of the projectile therethrough. Even under this latter circumstance the efficiency of the gun of this invention is extremely high, as can be readily appreciated and is much higher than any now known in the art.

While the gun illustrated in the drawings is of the single shot type, it will be appreciated that it may be modified for use as a repeater type without deviating from the invention hereof. The work applied by a user to compress the air in the cylinder, so as to attain a desired projectile velocity, is relatively small as compared to conventional compressed air guns, thus making this gun one that can be easily operated, and one in which several strokes of the scissors pump are not necessary in order to build up a satisfactory air charge to properly propel the pellet from the barrel. This results from the fact that the main factor regulating the velocity of the pellet is the mean effective air pressure exerted on it during its passage through the barrel, and therefore this gun can attain a pellet velocity equal to that of a conventional compressed air gun without the compression of air in the cylinder chamber to as high a pressure as in a compressed

5 air gun. This is possible because there is no drop in the initial air pressure, as in compressed air guns where there is a substantial drop in the initial pressure during the passage of the pellet through the barrel. Therefore, in conventional compressed air guns the initial pressure of the air charge must be high enough to provide an effective mean pressure equal to the initial pressure of the air charge in the gun of this invention, in order to obtain substantially the same pellet velocity.

10 It will also be understood that the velocity and pressure characteristics of this gun could be altered by varying such factors as the K factor of the spring, the length of barrel bore, the capacity of the chamber in which the air is compressed, the weight of the shot or pellet and the pressure to which the air is to be charged. By properly co-ordinating all of these elements, 15 various muzzle velocities can be attained, but in all cases the initial pressure of the air charge will be substantially maintained, as previously pointed out.

20 In the embodiment illustrated in Fig. 7, an air compressing piston or plunger 125 is disposed in the forward portion of the cylinder 15' and has its rod portion 127 connected to a pump mechanism of any suitable type such as the scissors mechanism previously described. A check valve 129 of any suitable type is disposed in the cylinder 15' rearwardly of the plunger 125 and forwardly of conduit means 131, which connects the rear portion of the cylinder 15' with the barrel 9', behind a projectile 87' disposed therein. A 25 plunger 27', similar to the plunger 27 previously described, is slidably disposed in the cylinder 15' rearwardly of the check valve 129. Spring 43' surrounds the rod 35' of the plunger 27' and the rear end of the spring 43' engages any suitable 30 cylinder abutment such as the wall portion 133. The plunger rod 35' extends through the abutment 133 so that the plunger 27' can move toward and away from the check valve 129. Suitable 35 firing valve means 135 is provided for normally closing the conduit 131 against the flow of air from the cylinder 15' to the barrel 9'. The valve means 135 may be of any suitable type and may be actuated in any desired manner, when the trigger of the gun is pulled, such as is shown in 40 the previous embodiment or as shown in the applicant's co-pending application for Mechanism for Maintaining Substantially Uniform Muzzle Velocity for Pneumatic Guns, Serial No. 762,391, filed July 21, 1947, and now abandoned, 45 so that the chamber between the check valve 129 closing the conduit 131 against the flow of air from the cylinder 15' to the barrel 9'. The valve means 135 may be of any suitable type and may be actuated in any desired manner, when the trigger of the gun is pulled, such as is shown in the previous embodiment or as shown in the applicant's co-pending application for Mechanism for Maintaining Substantially Uniform Muzzle Velocity for Pneumatic Guns, Serial No. 762,391, filed July 21, 1947, and now abandoned, 50 so that the chamber between the check valve 129 and the plunger 27' may be either partially or completely evacuated each time the trigger is pulled, in accordance with whether the gun is 55 of the single shot or repeater type.

60 In operation the chamber between the check valve 129 and plunger 27' is charged by operating the pump mechanism so as to cause the air compressing plunger 125 to compress air in the chamber between the check valve 129 and the plunger 125. When the air is compressed in this 65 latter chamber to a suitable pressure the check valve 129 is opened to permit the air charge to flow into the chamber between the check valve 129 and the plunger 27'. By operating the pump mechanism and air compressing plunger 125 one or more strokes, an air charge of a relatively large pressure can be built up in the cylinder chamber between the check valve and the plunger 27'. When the force exerted by the air charge in this 70 chamber exceeds the force exerted against the 75

plunger 27' by the spring 43', the plunger 27' will move rearwardly in the cylinder in the same manner as previously described, until a balanced condition is obtained between the spring and air charge. When the trigger is pulled so as to open the valve 135, to either evacuate a portion of the air charge in the chamber or all of the air charge, in accordance with the valve and firing arrangement used, the compressed air will flow from the cylinder chamber through the conduit 131, and into the barrel 9' behind the projectile 87', to propel the projectile from the barrel as previously described. As soon as the valve 135 is opened so that the volume of the chamber is increased and the pressure of the air charge tends to decrease the plunger 27' will move forwardly, under the action of the spring 43' to reduce the volume of the chamber as previously described in the embodiment shown in Figs. 1-6. In this way, as long as the valve 135 is open, the plunger 27' will be moved by the spring 43' to maintain the initial cylinder chamber air pressure in the barrel behind the projectile for at least a predetermined extent of the movement of the projectile through the barrel. As has been previously pointed out, this extent will depend upon the relative capacities of the barrel and the charge of air which is evacuated from the chamber and flows into the barrel. If the capacity of the air charge is less than the barrel, the initial air pressure will not be maintained throughout the entire extent of the movement of the projectile in the barrel, but if the capacity of the air charge is greater than the barrel capacity, then the initial cylinder compressed air pressure will be substantially maintained until the projectile is discharged from the barrel.

It will thus be appreciated that with the gun of this embodiment, the efficiency and substantial maintenance of the cylinder compressed air pressure will be maintained in the same manner as previously described, but in this embodiment a separate air compressing plunger or piston is employed for compressing the air in the chamber, which may be more advantageous in repeater type guns, although it will be readily appreciated that either embodiment may be used as either a single shot or a repeater type gun.

What is claimed is:

1. An air gun including a barrel adapted to receive a projectile, a chamber for the reception of a charge of compressed air, normally closed valve means connected with said chamber and barrel and adapted to be actuated so as to communicate said chamber with a portion of said barrel behind a projectile disposed therein, an element slidably connected with said chamber for movement toward and away from said valve means, movable plunger means disposed in said chamber, means providing a lost motion connection between said slidably element and said plunger means, means for moving said slidably element toward and away from said valve means so that said plunger means will move with said element away from said valve means, and so that said plunger means can move relative to said element when said element is moved toward said valve means, resilient means acting against the opposite side of said plunger means from the charge of compressed air and adapted to be compressed by movement of said plunger means caused by force exerted on said plunger means by the compressed air so as to equalize the force applied against said plunger means by the compressed air, and means for actuating said valve means so

as to permit the compressed air in said chamber to flow into said barrel portion, whereby said plunger and resilient means will substantially maintain the initial chamber compressed air pressure in said barrel for at least a predetermined extent of the movement of the projectile through the barrel.

2. An air gun including a barrel adapted to receive a projectile, a cylinder, normally closed valve means in said cylinder adapted to be actuated so as to communicate a portion of said cylinder on one side of said valve means with a portion of said barrel behind a projectile disposed therein, means for compressing air in said cylinder on one side of said valve means, including movable plunger means, an element slidably connected with said cylinder for movement toward and away from said valve means, means providing a lost motion connection between said slidably element and said plunger means, means for moving said slidably element toward and away from said valve means so that said plunger means will move with said element away from said valve means and so that said plunger means can move relative to said element when said element is moved toward said valve means, resilient means acting against the opposite side of said plunger means from said compressed air, said resilient means being preloaded or set so as to exert a predetermined force against said plunger means, said resilient means being adapted to be compressed by movement of said plunger caused by force exerted on said plunger by said compressed air so as to equalize the force applied against said plunger by the compressed air, and means including a trigger element for actuating said valve means so as to permit the compressed air between said plunger and valve means to flow into said barrel portion, whereby said plunger and resilient means will substantially maintain the initial cylinder compressed air pressure in said barrel for at least a predetermined extent of the movement of the projectile through the barrel.

3. An air gun including a barrel adapted to receive a projectile, a cylinder, normally closed valve means in said cylinder adapted to be actuated so as to permit a flow of air from one side of said valve means to said barrel behind a projectile therein, cage means slidably disposed in said cylinder on the one side of said valve means, a plunger slidably mounted in said cylinder between said cage means and valve means, means providing a lost motion connection between said cage means and plunger, a spring disposed between said plunger and cage means, means for moving said cage means toward and away from said valve means so as to compress air between said plunger and valve means, said spring being arranged and constructed so as to be compressible by the movement of said plunger after the air compressed between said valve means and plunger has reached a predetermined pressure, whereby to equalize the forces acting on each side of said plunger, and means for actuating said valve means so as to permit the compressed air between said plunger and valve means to flow into said barrel and propel the projectile therefrom, whereby as the compressed air in said cylinder moves into said barrel, said plunger will be moved toward said valve means by said compressed spring, so as to maintain the air pressure in said barrel substantially equal to the initial compressed air pressure in said cylinder for at least a predetermined extent of the movement of the projectile through the barrel.

4. An air gun including a barrel, a cylinder adjacent said barrel, normally closed valve means in said cylinder adapted to be actuated so as to communicate a portion of said cylinder ahead of said valve means with a rear portion of said barrel, cage means slidably disposed in said cylinder ahead of said valve means and movable toward and away from said valve means, a plunger slidably mounted in said cylinder between said valve means and said cage means, means including a resilient element between said plunger and cage means providing a yieldable lost motion connection between said plunger and said cage means so that said plunger will move with said cage means when the latter is moved away from said valve means and so that said plunger can move relative to said cage means against or under the action of said resilient element, means connected with said cage means for moving the same in said cylinder, whereby when said plunger is moved toward said valve means the air therebetween will be compressed and when the pressure of the compressed air exceeds the force normally exerted by the resilient element on the plunger, the plunger will move toward the cage means and will compress said resilient element until an equal force is exerted on each side of the plunger by the compressed resilient element and the compressed air, means including a trigger adapted to be actuated after the air is compressed between the plunger and valve means so as to actuate said valve means and permit the compressed air to flow into said barrel portion, and means for cocking said gun and positioning a projectile in said barrel for propulsion by said compressed air, whereby when a projectile is in said barrel the flow of compressed air into the latter will cause the projectile to move through said barrel toward the muzzle end thereof and whereby as the pressure of the compressed air in the cylinder between the valve means and plunger tends to decrease due to the flow of air into the barrel, the resilient element will move the plunger toward said valve means so as to substantially maintain the initial compressed air pressure in the cylinder and barrel for at least a predetermined extent of the movement of the projectile through the barrel.

5. In a fluid operated device, a cylinder, normally closed valve means in said cylinder adapted to be actuated so as to permit fluid to flow therethrough, cage means slidably disposed in said cylinder on one side of said valve means, a plunger slidably mounted in said cylinder between said cage means and valve means, means providing a lost motion connection between said cage means and plunger so that when said cage means is moved away from said valve means said plunger will be carried thereby and so that said plunger can move relative to said cage means, a spring disposed between said plunger and cage means, and means for moving said cage means and plunger toward and away from said valve means so as to compress fluid between said plunger and valve means, said spring being arranged and constructed so as to be compressible by the movement of said plunger after the air compressed between said valve means and plunger has reached a predetermined pressure, whereby to equalize the forces acting on each side of said plunger.

6. In a fluid operated device a cylinder, normally closed valve means in said cylinder adapted to be actuated so as to permit a flow of fluid therethrough, cage means slidably disposed in

said cylinder on one side of said valve means, a plunger slidably mounted in said cylinder between said cage means and valve means, means providing a lost motion connection between said cage means and plunger, a spring disposed between said plunger and cage means, means for compressing fluid between said plunger and valve means, said spring being preloaded or set between said plunger and cage means by said lost motion connection means so as to be compressible by the movement of said plunger caused by the force exerted thereon by said compressed air only after said compressed air force has exceeded a predetermined value, whereby to equalize the forces acting on each side of said plunger.

7. An air gun including a barrel adapted to receive a projectile, a cylinder, normally closed valve means in said cylinder adapted to be actuated so as to permit a flow of fluid from one side of said valve means to said barrel behind a projectile therein, cage means slidably disposed in said cylinder on the one side of said valve means, a plunger slidably mounted in said cylinder between said cage means and valve means, rod means having one end connected to said plunger and the opposite end connected with said cage means so as to provide a lost motion connection between said cage means and plunger, whereby when said cage means is moved away from said valve means said plunger will be carried thereby and whereby said plunger can move relative to said cage means, a coil spring disposed between said plunger and cage means, means for moving said cage means toward and away from said valve means so as to compress air between said plunger and valve means, adjustable means connecting said rod with said cage means so as to preload or set said spring, whereby said spring is compressible by movement of said plunger caused by force exerted thereon by air compressed between said valve means and plunger only after said force has reached a predetermined value, so as to equalize the forces acting on each side of said plunger, and means including a trigger element and hammer means for actuating said valve means so as to permit the compressed air between said plunger and valve means to flow into said barrel and propel the projectile therefrom, whereby as the compressed air in said cylinder moves through said valve means into said barrel said plunger will be moved toward said valve means by said spring so as to maintain the air pressure in said barrel substantially equal to the initial compressed air pressure in said cylinder for at least a predetermined extent of the movement of the projectile through the barrel.

WILLIAM S. WELLS.
